OIL DISPENSING ATTACHMENT FOR
GASOLINE PUMPS

William B. Thalman, Wilmette, Ill.

Application June 13, 1931, Serial No. 544,233
Renewed March 16, 1935

3 Claims. (Cl. 211—107)

This invention relates to improvements in holding and display racks for motor oil containers, and more particularly to detachable racks for gasoline filling pumps, which racks are arranged to hold a plurality of individual motor oil jars in visible and readily accessible position on the body of a dispensing pump.

Motor oil is usually dispensed at gasoline filling stations in relatively small quantities, and for this purpose refillable glass containers holding one quart are more or less generally used. These glass containers are usually kept in racks or holders which are either stationary or movable, but are neither readily accessible to the attendant for prompt service in supplying oil when needed, nor in prominent view of the customer as he drives up to the filling station.

In carrying out my invention, I provide a holder for the refillable glass jars or their equivalent, which attachment is secured directly to the body of the gasoline dispensing pump adjacent the base thereof, in which position it is not only convenient for giving immediate and prompt service by the attendant, but is in immediate view for advertising display to the motorist as he drives up to the filling station.

A further object of the invention is to provide an improved and simple construction for attachments of the character described, including means for guarding the spouts of the oil containers from engagement or fouling by the gasoline dispensing hose usually employed with such filling devices.

Other objects of the invention will appear from the following description.

The invention may best be understood by reference to the accompanying drawing, in which

Figure 1 is a plan view of an attachment constructed in accordance with my invention, but showing it removed from a gasoline dispensing pump.

Figure 2 is a side view of the attachment with a part section taken on line 2—2 of Figure 1, and illustrating the device as being mounted on the body of a gasoline dispensing pump indicated in dotted lines, and also showing a motor oil container in dotted lines in one of the compartments of the attachment.

Fig. 3 is a detail perspective view showing the construction of one of the compartments for the oil containers.

Referring now to details of the embodiment of my invention illustrated in the drawing, it will be understood that my attachment is especially designed to be applied to the body of an oil dis-

pensing pump of the usual type widely employed at roadside filling stations.

The body of the pump is indicated in dotted lines at 10, as shown herein being circular in shape, although it will be readily understood that said pump body may vary considerably in size and shape, and that the size and shape of my attachment may be varied accordingly. Said pump is provided, as usual, with a filling hose, indicated at 12, depending from the upper end of the pump.

The attachment illustrated herein is made up of upper and lower clamping rings 15 and 16 and an intermediate clamping ring 17, all adapted to be engaged about the body 10 of the dispensing pump. The attachment is preferably made in sections so as to be readily attached or removed. In the form shown, two semi-circular sections indicated generally at 11, 11 of similar construction, are clamped to each other at 20 adjacent ends by suitable means such as bolts 18, 18 and 18^a, 18^a. Outside the center ring 17 is formed a series of separate compartments for the oil containers 20, these compartments being indicated generally at 21, 21 and being formed 25 in the space between the inner clamping ring 17 and an outer intermediate ring 22. In the form shown, the inner and outer rings 17 and 22 are connected at opposite ends of each section by integral radially extending members 22^a so that 30 both rings may, if desired, be formed from a continuous length of stock.

The container compartments are made up of radially disposed bars 23, 23 extending between the inner and outer rings 17 and 22 and suitably 35 connected thereto as by welding, said radial bars being spaced circumferentially of each other as is best shown in Figure 3. Each of said bars has a depending upright bar 24 connected thereto, and said upright bars are connected at their 40 lower ends to a bottom supporting ring 25 which in the form shown is semi-circular and continuous throughout the length of each section of the attachment.

Connected to the bottom supporting ring 25 45 at points between each adjacent pair of upright bars 24, 24 is an L-shaped bar 26 which extends laterally and thence upwardly in position parallel with the outer ring 22 and connected thereto as by welding, so as to form a complete compartment within which the separate oil containers 20 may be received, as indicated in Figure 2.

The intermediate container structure is also connected to the upper and lower clamping rings 15 and 16 by a plurality of bars 28, 28, each 55

of which is connected at its upper and lower ends to the clamping rings 15 and 16, respectively, and are bulged outwardly around the outer intermediate ring 22 at a point opposite each of the side bars 23, 23 so as to define the sides of each of the oil compartments 21. The bulging side bars 23 are thus spaced so as to readily permit access to each of the container compartments 21. An additional guard ring 28^a is connected to the side bars 23 above the upper end of the oil container spouts 20^a to form a guard for said spouts from contact or fouling by the gasoline dispensing hose, indicated at 12 in the drawing, and which as usual depends from the dispensing fixture at the upper end of the dispensing pump 10.

As a further feature of my invention, I provide a series of detachable spout caps 29, 29 connected by flexible chains 30, 30 or their equivalent to the upper clamping ring 15, one of such spout caps being provided for each of the compartments 21 as shown. The spout caps are thus in position to be readily placed upon each of the spouts 20^a when its respective container 20 is in place on the rack as indicated in dotted lines in Figure 2. This protects each oil container from rain, dust or dirt.

It will now be readily understood that were it not for the provision of the bulging guard bars 23, 23 and guard ring 28^a, or their equivalent, the gasoline dispensing hose would constantly have a tendency to get caught in or about the oil container spouts, and dirt from the hose would be transferred to the oil containers and find its way into the oil, and on the other hand oil from the containers would get upon the hose. These objections are all eliminated by the protecting guard means described.

Although I have illustrated and described one

particular embodiment of my invention, it will be understood that I do not wish to be limited to the exact construction shown and described, but that various changes and modifications may be made without departing from the spirit and scope of my invention. 5

I claim:

1. A motor oil container rack comprising a plurality of detachable split sections adapted to be connected around an upright standard, each of said sections comprising two vertically spaced split rings, a plurality of oil container receiving compartments mounted on the lower ring, and a plurality of closure members flexibly connected to said upper ring in position to detachably engage the upper ends of said oil containers when disposed in their respective compartments. 10

2. An attachment for gasoline dispensing pumps consisting of a split upper and a split lower ring detachably engageable about the body of said pump and an intermediate rack structure including a split inner and a split outer ring having a plurality of compartments for oil containers formed therebetween, and a plurality of upright bars integrally connecting said upper, 15 outer and lower rings together.

3. A motor oil container rack comprising a pair of companion sections adapted to be connected around an upright standard, at least one of said sections comprising a split upper and a split lower ring and an intermediate rack structure consisting of a split inner and a split outer ring having a plurality of compartments for oil containers formed therebetween, and a plurality of upright bars defining the sides of said compartments and integrally connected between said upper, outer and lower rings. 30 35

WILLIAM B. THALMAN.
